MOISTENING OF TEXTILE FIBERS AND YARNS

Charles Friedrich Dülken, Arlington, N. J.

Application February 19, 1932, Serial No. 594,100,
and in Germany April 11, 1931.

8 Claims. (Cl. 28—58)

This invention relates to a method of and means for moistening textile fibers and spun yarns in hank form. Its object is so to treat the textile materials that the moistening shall be in as uniform a manner as possible with the minimum amount of damage and the maximum saving in labor and a greatly increased output.

In the method commonly employed hitherto the hanks were usually spaced out on a table and sprayed by hand with a suitable implement. It has also been proposed to expose the material or yarn to be moistened to the action of steam while balled up or to convey it through an elongated closed box, in which it is treated with moist air. The known methods and apparatus, however, have various disadvantages. The moistening takes place in a non-uniform manner, with the consequence that some parts of the material absorb too little and others too much moisture.

10 The method is somewhat inconvenient to carry out, so that the labor and operative costs are high. The arrangements are costly and therefore entail high initial outlay. Furthermore, it frequently occurs that the material to be moistened gets soiled with rust or oil from the apparatus or is otherwise damaged.

15 The method according to the invention avoids these disadvantages through the hanks of material to be moistened being conveyed past one or more moisture-applying places. In a particularly suitable way of carrying out the invention the suspended hanks are conveyed past the moisture applying place or places. Preferably several hanks are suspended next to one another.

20 In another way of carrying out the invention the hanks are moistened on a vertical part of their path, the arrangement being such that they can be moistened simultaneously from both sides.

25 A further way of carrying the invention into effect consists in this, that the hanks, while being moistened, are loosened up by a stream of air. Preferably on the vertical part of their path the hanks are simultaneously moistened from both sides and exposed to the action of the blast from above or below or from above and below.

The apparatus for carrying out the method according to the invention is characterized by a conveying device with driving members for the hanks and one or more moistening arrangements 30 along which the conveying device travels.

A simple constructional form of the invention is one in which there are two endless conveyor chains or the like which are arranged parallel to one another at a certain distance apart and 35 which are provided at certain intervals with

hook-shaped driving members which engage transverse bars which are adapted to be placed loosely in the device and from which the hanks are suspended, the bars with the hanks being released from the conveyors after the moistening operation. The path along which the transverse bars are conveyed is preferably divided into separate part paths each with endless continuously running conveying means, sliding paths being provided between the separate part paths for 60 passing the transverse bars from one conveying means to the other. The velocities of the conveying device and of the spraying device, are regulable independently of one another, so that an accurately adjustable quantity of moisture 65 can be supplied.

In a particularly suitable constructional form of the device the path through which the transverse bars supporting the hanks are moved by the conveying means forms a completely or nearly 70 completely closed circuit, the place where the bars are fed to the device being opposite the place of delivery. This arrangement has the advantage that a single attendant can both feed the bars to the device and remove them from it without 75 changing his position, which considerably simplifies the work.

The invention enables the hanks of textile material to be uniformly moistened over their entire length, such moistening being regulable within 80 wide limits. There will be no places which receive too much moisture and none which receives too little moisture. The suspended hanks do not come in contact with the metal parts of the device so that they cannot be soiled either by 85 rust or oil or the like. The attendance required for the device is reduced to a minimum which greatly increases the efficiency.

The invention is illustrated in the accompanying drawing by two constructional examples. 90

Fig. 1 being a diagrammatic side view of the main parts of the machine with the frame removed.

Fig. 2 a general side view of the machine frame,

Fig. 3 a view of one of the bars for suspending 100 the hanks of yarn, and

Fig. 4 another way of suspending the hanks of yarn from the bars.

The apparatus for carrying out the method according to the invention consists of an iron 105 framework which has the general form of a doorway. In Fig. 2 one upright of the doorway is marked 1, the other 2, the top of the doorway 3. The upright 1 which contains the actual moistening device may have its sides covered with sheet 110

metal. At A at the upright 1 is the place where the material to be moistened is fed in and at E on the upright 2 the place of delivery.

In the upright 1 a continuously operating conveyor is used, which consists of two endless conveyor chains 4 arranged parallel to and at a distance from one another and which are provided at regular intervals with hook-shaped driving members 5. The conveyor chains are led around 10 chain wheels or guiding rollers 6 which are mounted on transverse shafts in the machine frame. One pair of chain wheels is driven by a motor (not shown). Below the lower horizontal stretch of the conveyor chains a guiding 15 path 7 is disposed which is open at the feeding in place A for the insertion of the transverse bars from which the textile material is suspended.

The material in the form of hanks to be moistened is suspended from transverse bars 8 of 20 wood or some other material, from which the hanks 9 hang down freely. As shown in Fig. 3 several hanks 9 are suspended next to one another. The transverse bars 8 are placed at A with their ends on the guiding paths 7 and slide 25 down under the action of gravity. The ends of the bars are then engaged each by a hook 5 on one of the two conveyor chains 4 and are carried along by them, the weight of the bars resting on the guiding paths 7.

30 As will be seen from Fig. 1 the moistening of the hanks takes place on the left hand vertical stretch of the conveyor chains 4. The moistening device consists for instance of two containers 10, which contain the moistening liquid in which 35 the rotating feed drums 11 are immersed. These drums thus become coated on their surface with the moistening liquid. Above the drums 11 are mounted two rapidly rotating brush rollers 12 which flick the liquid off the surface of the drums 11 and spray it on to the hanks as they pass. The drums 11 and the rollers 12 are driven by the main drive (not shown). The hanks are thus sprayed simultaneously from both sides over their 40 entire length. In place of the moistening device 45 shown ordinary spraying nozzles or the like might be used.

Below the vertical stretch of the conveyor chains 4 in which the moistening of the hanks of 50 yarn takes place is a blower 13 which directs an upward vertical stream of air against the hanks to be moistened. By this means the hanks are loosened up so that the sprayed on moistening liquid impinges uniformly over the entire 55 surface of the textile surface. In place of the blowers 13 ordinary air nozzles might be used, fed from an air compressor. The blast might also be directed at this place against the hanks from above and below.

60 After the hanks have passed through the moistening place they travel along the upper horizontal part of the upright 1 till they reach the point B. At this point the bars 8 are released from the driving members 5 and slide under gravity over a guiding path 14 to the upper transverse member 3 of the machine frame. A second 65 endless chain conveyor 15 is there provided, which is fitted in a similar way with driving members 5 which engage the bars as they arrive and carry them along horizontally.

70 At the end of the horizontal stretch the bars with the hanks of yarn are transferred at C to another conveyor 16 which is mounted in the upright 2. This conveyor 16 is also provided with driving members 5 and conveys the textile material vertically downwards where the bars 8 are

finally delivered to the fixed guiding path 17 which leads them to the place of delivery E, where the bars with the fully moistened hanks of yarn are removed. The place of delivery E lies opposite the feed place A in the interior of the 80 doorway formed by the machine frame so that the two places can be served by a single man.

As will be seen from Fig. 2 the guiding paths 7, 14 and 17 may be so constructed that a single continuous guide is formed from the point A to 85 the point E. This ensures great reliability of operation. The arrangement of the driving members 5 on the conveyor chains should be made such that the passage of the bars 8 from one part conveyor to the next takes place without any shock and at a uniform velocity. The 90 velocities of the conveyor 4 and of the moistening device 11, 12 are preferably regulable independently of one another, so that the amount of moisture to be supplied to the textile material 95 can be accurately regulated as required.

In Fig. 4 another constructional form is illustrated. In this form the transverse bars 8 are provided with separate hooks 18 from which the hanks of 100 yarn 9 are suspended transversely, so that they offer their widest side to the moistening sprays.

The driving members 5 are shown as open hooks. Instead of this they may be so constructed that they form two oppositely directed 105 claws which engage the ends of the bars 8 like shears and thus hold them fast.

What I claim is:

1. An apparatus for moistening textile fibers and yarns in the form of hanks, comprising in combination moistening means, endless conveyor chains spaced apart parallel to one another for conveying the hanks past the moistening means, loose transverse bars, from which the hanks are suspended, hook-shaped driving members fixed on the chains opposite one another at definite intervals and adapted to engage round the said loose bars for carrying them past the moistening means and to release them after the bars have passed the moistening means, as set forth.

2. An apparatus for moistening textile fibers and yarns in the form of hanks, comprising in combination moistening means, endless conveyor chains spaced apart parallel to one another for conveying the hanks past the moistening means, loose transverse bars, from which the hanks are suspended so as to present their widest side to the moistening means, hook-shaped driving members fixed on the chains opposite one another at definite intervals and adapted to engage round the said loose bars for carrying them past the moistening means and to release them after the bars have passed the moistening means, as set forth.

3. An apparatus for moistening textile fibers and yarns in the form of hanks, comprising in combination moistening means, endless conveyor chains spaced apart from one another so as to travel in vertical planes for conveying the hanks past the moistening means, loose transverse bars from which the hanks are suspended, guiding rails fixed below the horizontal stretches of the conveyor chains, hook-shaped driving members fixed on the chains opposite one another at definite intervals and adapted to push the bars along the 145 said guiding rails during the horizontal part of their path, to support them during the vertical part of their path and to release them after they have passed the moistening means, as set forth.

4. An apparatus for moistening textile fibers

- and yarns in the form of hanks, comprising in combination moistening means, endless conveyor chains spaced apart from one another so as to travel in vertical planes for conveying the hanks past the moistening means, loose transverse bars 5 from which the hanks are suspended, slightly inclined guiding rails fixed below the substantially horizontal stretches of the conveyor chains, along which the bars can slide downwards under gravity during the substantially horizontal portion of 10 their path, hook-shaped members fixed on the chains opposite one another at definite intervals and adapted to support the bars during the substantially vertical part of their path and to release them after they have passed the moistening means, as set forth. 15
5. An apparatus for moistening textile fibers and yarns in the form of hanks, comprising in combination moistening means, transverse bars from which the hanks are suspended, a series of 20 continuously travelling endless conveyors for conveying the bars with the hanks past the moistening means and sliding paths disposed between the separate conveyors for guiding the bars from one conveyor to the next, as set forth. 25
6. An apparatus for moistening textile fibers and yarns in form of hanks, comprising in combination moistening means, transverse bars from which the hanks are suspended, a series of continuously travelling endless conveyors for conveying the bars with the hanks past the moistening means, sliding paths disposed between the separate conveyors for guiding the bars from one conveyor to the next, and driving members fixed 30 at intervals to the conveyors, which are adapted 35
- to engage with the said bars and are spaced in such a manner that the bars, on arriving at the end of one conveyor, are received by the next without any shock and at the same speed of travel by the next conveyor, as set forth. 40
7. An apparatus for moistening textile fibers and yarns in the form of hanks, comprising in combination transverse bars from which the hanks are suspended, conveying means to cause the bars to travel along a path, a portion of which is vertical, moistening means on opposite sides of the said vertical portion of the path for simultaneously and completely moistening the sides of each hank and a blower having its delivery opening in the said vertical portion of the path and equidirectional therewith so as to loosen the hanks while the latter are being moistened, as set forth. 45
8. An apparatus for moistening textile fibers and yarns in the form of hanks, comprising in combination a framework in the form of a doorway, conveying means adapted to convey the hanks past in a substantially closed circuit about the frame, moistening means arranged on one side of the frame and positioned on opposite sides of the conveying means, a blower for loosening up the material of the hanks at the time the hanks are being moistened, and the place where the hanks are fed to the conveying means being disposed on one side of the doorway and the place where they are removed from it after treatment 50 being on the other side of the doorway so that one person can attend to the feeding and removing operations, as set forth. 55
